UNITED STATES PATENT OFFICE.

CARL ABSMEIER, OF GRAND RAPIDS, MICHIGAN.

POOL-TABLE REGISTER.

Application filed September 17, 1921. Serial No. 501,836.

To all whom it may concern:

Be it known that I, CARL ABSMEIER, a citizen of the United States of America, residing at Grand Rapids, in the county of Kent and State of Michigan, have invented certain new and useful Improvements in Pool-Table Registers; and I do hereby declare the following to be a full, clear, and exact description of the invention, such as will enable others skilled in the art to which it appertains to make and use the same.

This invention relates to a register particularly adapted for use with pool tables, though not limited in use to the one article mentioned. It is a primary object and purpose of the present invention to make a register which will register the number of games played and at the same time indicate the value of the game played so that the total taken in for each table at the end of a day or any other period of time may be computed, thus safeguarding the owner of the tables against dishonesty on the part of attendants. A further object of the invention is to provide means whereby the attendant must operate the register in order to use the rack used for setting up or racking the balls used, the rack being ordinarily locked in place on the register, to unlock and release which the register must be operated to record the game played. These and many other objects and purposes not at this time specifically stated will appear fully and in detail together with novel constructions for attaining the same, as understanding of the invention is had from the following description, taken in connection with the accompanying drawings, in which,

Fig. 1 is a front elevation of the register, its front casing cover being removed to show the interior structure, and parts of the table and lower part of the casing being in vertical section.

Fig. 2 is a fragmentary plan view of the indicator mounted on the table to show from above.

Fig. 3 is a plan view of the movable indicator member.

Fig. 4 is a vertical section through the register and adjacent portions of the table.

Fig. 5 is a fragmentary vertical section, similar to Fig. 4, showing the lower part of the register with the mechanism in a different position from that shown in said Fig. 4.

Fig. 6 is a horizontal section taken substantially on the plane of line 6--6 of Fig. 1.

Fig. 7 is a fragmentary front elevation of the register mechanism after one of the register units has been operated, and

Fig. 8 is a like view showing the register mechanism when the middle unit thereof has been operated.

Like reference characters refer to like parts in the different figures of the drawings.

The pool table 1 may be of any usual construction having a border rail 2 on the under side of which the register casing is mounted. The casing in which the mechanism is mounted includes a vertical back plate 3, having a forwardly turned lug 4 at its upper edge immediately under the rail 2, while a short distance above the lower edge of the plate and adjacent each side edge thereof an integrally cast member 5 projects to the rear for a short distance, is then turned downwardly, as indicated at 6 to below the lower edge of plate 3 and then turned forwardly, making a supporting lug or shelf 7. The front face of the plate 3 at each side is formed with guide ribs 8 for the positioning of the casing cover, comprised of a front vertical plate 9 having sides 11 extending inwardly to plate 3 and bearing thereagainst alongside of the ribs 8, and also having a bottom inwardly extending flange 10 which passes over the lugs 7 to the parts 6, as shown in Fig. 4. One side of the rack 12 is adapted to be placed over the lugs 7 and under the flange 10.

The rack is held against removal from the lugs 7 by latching means consisting of a latch bar 13 mounted above the flange 10 and provided at its ends with depending latch projections 14 which pass through suitable openings made in the flange 10. A rod 15 is connected to and extends upwardly from each end of bar 13, having a slideable mount in lugs 16 and 17 cast with and projecting forward from the back plate 3. A spring 18, around each rod 15 and located between the upper lug 16 and a pin 18^a passing through the rod, serves to normally hold the latch bar in lower position.

At each end of the latch bar, a lug 19 having an opening 20 therethrough, is positioned, a locking rod 21 being adapted to enter the opening to thereby hold the latch bar locked in lower position. The rods 21 are slidably mounted through lugs 22 extending upwardly from the flange 10 and at

their rear ends loosely enter openings 23 made through the parts 6. Rods 21 normally are impelled forward by springs 24 located between parts 6 and arms 25 secured 5 to the rods. The arms 25 extend upwardly and toward each other at an angle to the vertical and at their upper ends are fixed to rods 26 which are bent backwardly at right angles from a rod 27 which is located horizontally near the front side 9 of the casing. 10

The rods 26 loosely enter openings 28 made through parts 6, and springs 29 located between the upper ends of arms 25 and said parts 6 normally serve to force the rods 26 15 and connecting rod 27 forward, as is evident. With the latch bar 13 in lower position, the effect of springs 29 and 24 is to move the front ends of rods 21 into the openings 20 to lock the latch bar in lower position, and 20 a rack 12 located back of the projections 14 cannot be removed.

In the upper side of each rack supporting lug 7 a recess 30 is made in which a member 31 is located, the forward upper portion of 25 which is formed with an inclined upper side 32. Members 31 are secured on rods 33 mounted vertically and pass loosely through part 6 below the rods 21 and also through nuts 35 screwed into the lower sides of lugs 30 7. A spring 34 is located around each rod 33 between each nut 35 and member 31 tending to elevate the member and rod. The upper end of each rod 33 is formed with a reduced portion 36 shaped to enter a recess 35 in the lower side of the adjacent rod 21 when such rod has been moved backwardly to unlocking position. When the rack 12 is placed on its supporting lugs 7, it rides against the inclined upper sides 32, thereby forcing 40 members 33 and attached rods 33 to the lower position shown in Fig. 4. When the rack is removed, springs 34 are free to elevate said members and rods to the position shown in Fig. 5.

45 The latch bar 13 carries three upwardly extending headed pins 37, 38 and 39, the same being spaced apart at equal distances. Pin 37 passes through an ear 40 turned at right angles from the lower end of a vertical bar 41 which, at its upper end, has a second laterally extending ear 42 slidably mounted on a vertical guide rod 43. There are two of the rods 43 spaced apart and secured at their upper ends to a cross bar 44 50 which is attached to the back plate 3, and at their lower ends to lugs 45 cast with the plate. A rack bar 46 having a rack 47 cut in one side is secured to and extends upwardly from bar 41, passing through a horizontal guide bar 48 connected to back 3. The upper end of the rack bar is operatively connected by links 46^a with a number register 49, the design being such that reciprocation of the rack bar is registered on the 55 number register, the specific construction of

which is no part of the present invention. Rack bar 46 and attached parts are normally held in a lower position by a spring 50 mounted between the bar 48 and a lug 51 projecting from the rack bar, and located 70 around a rod 52 which is secured to the lug 51 and passes upwardly through the bar 48. The cover plate 9 has an opening 53 there-through through which the numbers showing on register 49 are visible. 75

A gear 54 is in mesh with the rack at 47, being mounted on a shaft 55 which is rotatably mounted at its rear end in the back plate 3 and at its front portion in an inwardly projecting boss 56, the shaft extending 80 through said boss and being formed at its front end with a triangular shaped end 57 with which a suitable key 58 may engage for manually turning the shaft and gear to operate the rack bar. The shape of the shaft at 85 57 may be varied without changing the invention.

Pin 39 on the rack bar 13 also passes through an ear 59 turned at right angles at the lower end of a vertical bar 60, it having 90 at its upper end a second laterally projecting ear 61 slidably mounted on the other vertical guide rod 43. A rack bar 62 having a rack 63 at one side is connected with bar 60 at the upper end thereof and passes through bar 48, 95 being connected by linkage 63^a with a second number register 64 mounted back of cover plate 9, the numbers being visible through an opening like that shown at 53. A spring 65 between bar 48 and a lug 66 100 projecting from the rack bar 62 serves to normally hold the rack bar and attached parts in lower position. The spring is located around a rod 67 attached to lug 66 and passing upwardly through bar 48. A gear 68 mounted on a key shaft 69 operates the rack bar through the medium of a key. In fact this second registering unit is practically identical in structure with the one first described, except for slight modifications due to the different locations of the two units. 105

A rod 70 is slidably mounted through bar 44 midway between its ends, a rack bar 72 formed at one side with a rack 73 connecting therewith at its upper end. The lower end of rod 70 is provided with a head 71 having parts extending laterally at each side. A gear 74 mounted and operated the same as gears 54 and 68 meshes with the rack 73 for operating rack bar 72. A spring 75 between the bar 48 and a lug 76 projecting from the bar 72 and around a rod 77, serves to hold the rack bar and attached parts in lower position. A bar 78 connects at its upper end with the lower portion of the rack bar 72, is bent forward to pass over the bar 44 and extends downward to the central pin 38, being formed at its lower end with an ear 79 through which the pin passes. A 110

third number register 80 is operated by reciprocal movements of the rack bar 72, through suitable link connections 72^a like registers 49 and 64 and the numbers are likewise visible through an opening in the front side of the casing.

Two rack bars 81 and 82 are slidably mounted on rods 43, the inner adjacent sides of said bars being equipped with rack teeth 10 which engage a pinion 83 fixed on a shaft 84 which is mounted horizontally between the back and front of the casing. A bevelled gear 85 is secured to the shaft in front of pinion 83 and meshes with a second bevelled gear 86 fixed at the lower end of a vertical shaft 87, the same extending upwardly through the casing, lug 4, and an opening made in the rail 2, to a shallow recess 88 cut in the upper side of the rail. An indicator plate 89 having a series of numbers indicative of the prices of the games played is attached to the upper end of shaft 87, lying within the recess and being normally concealed from view by a plate 90 covering the recess. A circular opening 91 is made through the plate through which one indicating number on plate 89 only can be seen. The means used to mount rack bars 81 and 82 on the rods 43 consists of upper brackets 30 82 and 93, the former being connected at the upper end of rack bar 81 and having laterally extending portions at each side lying above the ear 61 and head 71, as shown, while the latter has similar ears coming 35 above ear 42 and said head 71. For the lower ends of the rack bars brackets 94 are used, the only function of which is to slidably mount the lower ends of the rack bars on rods 43.

40 Each of the bars 41, 60 and 78 carries a cam member 96 at its lower end. The cam members are located at the lower ends of and in front of the bars being connected by forwardly extending arms 95 formed integral 45 with said bars. Each cam member has an inclined rear side 97 for a distance, below which the rear side of the cam member is vertical. A bearing band 98 is positioned in front of the cam members to hold them 50 against spring away from the rod 27 which is normally located directly at the upper limit of the inclined cam portions 87 of said members.

55 With the mechanism in the position shown in Figs. 1 and 4, the latch bar 13 is in latching position, the rack 12 being held back of the latching lugs or dogs 14 and the latch bar is locked in position by locking rods 21. This is where the rack is placed immediately 60 after the balls have been racked at the beginning of a game. After the game is finished, and the rack is to be used again for the starting of a new game, the attendant, using key 58, places it in conjunction with one of 65 the registering units corresponding with

the price of the game to be played and turns the same. For instance, if a twenty five cent game is to be played, the key is fitted to shaft 55 and it is turned to elevate rack bar 46 to the position shown in Fig. 7. 70 During the time that ear 40 is traversing pin 37 until it engages against the head thereof, the cam member 96 on the bar 41 is elevated, the inclined side 97 thereof bearing against rod 27 and forcing it and its attached end rods 26 back, this carrying the locking rods 21 back also and unlocking them from the latch bar. With the continuation of the upward movement of the rack bar 46 and attached bar 41, the ear lifts the latch bar so as to bring the projecting dogs 14 above the lower side of flange 10, freeing the rack 12 for removal. At the same time, the part 42 engages under the bracket 93, lifting rack bar 82, whereby pinion 83 is rotated, thus turning shaft 87 so as to bring the numeral 25 on the indicator plate 89 directly under the opening 91 in cover plate 90. The other rack bar 81 is correspondingly lowered to the position shown in Fig. 7. With the removal of the ball rack 12, the members 31 are released and rods 33 move upwardly, the ends 36 thereof engaging with and holding locking rods 21 in unlocking position, as shown in Fig. 5, the rod 27 remaining stationary or dwelling behind the vertical rear side of the cam member 96. When the rack is used and the balls properly positioned on the table, it is then placed over the supporting lugs 7 and forced back to the position shown in Fig. 4, the latch bar, being unlocked, elevating to permit passage of said rack 12 which coming to the inclined upper sides of members 31, depresses them, unlocking the rods 21 which immediately move forward and lock the latch bar against upward movement. The movement of the bar 46 serves to move the number register 49 so as to indicate one more than it registered before. 100

105 After this operation, the bars 81 and 82 remain in the position to which they have been moved, the indicator plate showing the price of the game being played. If the succeeding game is to be of the same price, the bars 81 and 82, and the mechanism operated thereby are not moved, the same indication remaining. If the middle rack bar 72 is actuated, the latch bar is unlocked and raised as before, but the head 71 engaging under bracket 92 moves the indicator rack bars 81 and 82 to the position shown in Fig. 8, and the indicator plate shows the numeral 110 15 through opening at 91. Or if the bar 62 is elevated, with the indicator mechanism in the position shown in Fig. 7, the part 61 engaging under bracket 92 moves the bars 81 and 82 so as to reverse the positions occupied by them, from that shown in Fig. 7, 115 120 125 130

and the numeral 10 appears through opening 91.

In any case, the registers at 49, 80 and 64 show the numbers of games of each kind played, from which it is easy to compute the total taken for playing. The rack 12 will be chained or otherwise attached to the table so that it is necessary to return it to the register after use. The construction is a practical safeguard against dishonesty of attendants, a check being kept on the games played and the amounts taken in, similar to cash registers of various kinds in stores, on street cars and the like. The invention is defined in the appended claims and I consider myself entitled to all forms of construction coming within their scope.

I claim:

1. In combination, a casing, a plurality of registering counters located within the casing, said casing having openings to show the numbers on the counters, a plurality of vertically reciprocal bars mounted for vertical movements within the casing, one for each counter, means connecting the bars with the counters to operate the same on movements of said vertical bars, a latch bar located within the casing horizontally above the bottom of the casing, said latch bar having locking dogs projecting therefrom through the bottom of the casing, means normally holding the latch bar in lower position, lugs located under the bottom of the casing on which a pool ball rack may be placed back of the locking dogs, means operatively connecting each of the vertical bars with the latch bar to elevate the latch bar on upward movement of any one of the vertical bars, and means for individually elevating the vertical bars, substantially as described.

2. In combination, a casing, a registering counter therein, said casing having an opening to show the numbers on the counter, a latch bar mounted in the lower portion of the casing having latch dogs extending through the bottom of the casing, lugs located under the bottom of the casing on which a pool ball rack may be placed behind the dogs, a vertically reciprocal bar within the casing, a headed pin on the latch bar, the pin passing through the lower end of the vertical bar, means for elevating the vertical bar, spring means tending to keep said vertical bar in lower position, and means connecting the upper end of the vertical bar with the counter to operate the

counter by movement of the vertical bar, substantially as described.

3. In combination with a pool or like table, a plurality of registering counters, a latching means for holding a pool ball rack against removal, individual means for separately operating the counters, and connections between the latching means and each of said individual means for moving the latching means to position to release the rack on operation of any one of said individual means, substantially as described.

4. In combination, a hollow casing, a latch bar located horizontally in the lower part of the casing having latching dogs projecting therefrom through the bottom of the casing, lugs located under the casing on which a pool ball rack may be placed back of the locking dogs, spring means normally holding the latch bar in lower position, a plurality of headed pins projecting upwardly from the latch bar, a plurality of vertical bars having laterally turned ears at their lower ends through which said pins pass, a rack bar attached at the upper end of each vertical bar, a pinion in engagement with each rack bar, a shaft on which each pinion is mounted, said shafts at their front ends being formed to receive an operating key, and a registering counter operatively connected with the upper end portion of each rack bar, substantially as described.

5. A construction containing the elements in combination defined in claim 4, combined with locking rods adapted to engage with the latch bar to hold it in lower position, and means operated by movement of any one of the vertical bars in an upward direction for retracting the locking rods previous to upward movement of the latch bar, substantially as described.

6. A register for a pool table or the like, comprising a plurality of registering counters, a casing enclosing the same, latching means at a side of the casing for engaging with and holding a pool rack ball against removal, individual means for operating each counter, each including a member adapted to be operated by a key extending to the front of the casing, and connections between the latching means and each of said individual means for moving the latching means to release the rack on operation of any one of the individual means.

In testimony whereof I affix my signature.

CARL ABSMEIER.
